(57) **CLAIM**

The ornamental design for a streetlight-mountable wireless networking device, as shown and described.

DESCRIPTION

FIG. 1 is a perspective view of a streetlight-mountable wireless networking device showing our new design.

FIG. 2 is a front elevational view thereof.

FIG. 3 is a rear elevational view thereof.

FIG. 4 is a top plan view thereof.

FIG. 5 is a bottom plan view thereof.

FIG. 6 is an enlarged scale partial cross-sectional view thereof taken along line 6-6 of FIG. 5.

FIG. 7 is a left side elevational view thereof; and,

FIG. 8 is a right side elevational view thereof.

The dot-dash broken line defines the bounds of the claimed design while all other broken lines are directed to environment. None of the broken lines form any part of the claimed design.
